Charles Hough of Williamsburgh, No. 4

Letter Patent No. 6265, dated Dec. 11, 1866

Design for an Oil Can

The whole or part of this letter patent and making part of the same.

To all whom it may concern:

Be it known that at the office of A. Hogg, printer
in the city of Williamsburgh, County of Kings, and State of New York,
have invented and arranged a new and original Design for Oil Cans; and I do
hereby declare that the following is a full, clear and exact description
of enabling those skilled in the art to fully understand and use the
same, reference being had to the accompanying drawing in which:

Fig. 1 represents a side elevation of the invention.

Fig. 2, a plan or top view of the same.

Similar letters of reference in both figures indicate like parts.

The principal feature of this Design is a tube or tube extending from
the top of the oil can, through the side of the can to a point about
the appearance of a beak. The tube is bent from the bottom of the
can, and its top curves over the end of the can a tube, and by said end or
tube the appearance of firmness and safety in the position of the tube
is produced. Across the top of the oil can is a short transverse pipe
carrying which a cork stopper is inserted.

It operates on oil can the top and bottom of which are pro-
moted by mouldings as shown. Across the lower part of said can
extends the spout B, tapering towards its mouth which is curved as
a beak, and from the top of the can extends the tube C, through the
spout, giving to said spout the appearance of the beak of a bird, and
furthermore by this tube a certain sense of safety and firmness is produced
in the position of the spout.

A to a conical shaped tubular projection D, rises from the top of
the can, and into this tube the stopper E, is inserted.

What I claim as new and distinctively my invention is:
The Design for an Oil Can as shown and described.
